L. E. BIGELOW,
THROTTLE VALVE LOCK FOR MOTOR VEHICLES,
APPLICATION FILED DEC. 15, 1919.

1,403,379.

Patented Jan. 10, 1922.

UNITED STATES PATENT OFFICE.

LEROY E. BIGELOW, OF MEDFORD, OREGON.

THROTTLE-VALVE LOCK FOR MOTOR VEHICLES.

1,403,379.

Specification of Letters Patent. Patented Jan. 10, 1922.

Application filed December 15, 1919. Serial No. 344,921.

To all whom it may concern:

Be it known that I, LEROY E. BIGELOW, citizen of the United States, residing at Medford, in the county of Jackson and State 5 of Oregon, have invented certain new and useful Improvements in Throttle-Valve Locks for Motor Vehicles, of which the following is a specification.

This invention relates to an improved 10 throttle valve lock, being particularly designed for use in connection with the throttle valves of motor vehicles although, as will later appear, the device may be otherwise employed, and has as one of its principal 15 objects to provide a simple and efficient device of this character which will effectually prevent the unauthorized use of the vehicle.

The invention has a further object to provide 20 a device adapted to be interposed between an engine carburetor and intake manifold and which may be readily operated to block movement of the throttle valve of the carburetor.

25 And the invention has a still further object to provide a device which may be readily employed in connection with substantially any conventional type of internal combustion engine.

30 Other and incidental objects will appear hereinafter.

In the drawings:

Figure 1 is a side elevation showing my improved device mounted between the carburetor and intake manifold of a motor vehicle engine, the engine not being illustrated,

Figure 2 is a fragmentary section taken centrally through the device,

Figure 3 is a front elevation illustrating 40 the device detached, and

Figure 4 is a detail perspective view particularly illustrating the valve blocking mechanism of the device.

In order to facilitate an accurate understanding 45 of the construction, manner of use and operation of my improved device, I have, in the drawings, shown the invention in connection with a carburetor 10 and intake manifold 11 of a conventional type of 50 motor vehicle engine, the engine not being illustrated since it forms no part of the present invention. As is usual, the carburetor is provided with a discharge outlet 12 the flange 13 of which normally mates with 55 and is secured against the flange 14 of the manifold. Mounted within the outlet 12 is

a throttle valve 15 of the butterfly type. This valve is carried by a stem 16 journaled through the outlet and connected to one end of said stem is a throttle valve lever 17, this lever being operable for controlling the valve and thus, in turn, controlling the operation of the engine.

In carrying the invention into effect, I employ a body block 18 shaped to fit between the flanges 13 and 14 of the carburetor and intake manifold respectively, mating therewith. Securing said block in position and connecting the carburetor with the manifold are bolts or other suitable fastening devices 19 extending through said flanges and the block. The block may be formed of metal, fiber or any other approved material and centrally is provided with a passage 20 therethrough registering with the 65 passages of the manifold 11 and outlet 12. Journaled through the body block is a transversely extending shaft 21 extending across the upper side of the passage 20. At one end the shaft is provided with a socket 22 70 and surrounding the adjacent end portion of the shaft is a boss 23 extending laterally from the body block. Suitably fixed to the shaft within the passage 20 is a locking member or arm 24 and arranged to coact 75 with this arm is a resilient retaining catch 25 therefor. As particularly shown in Figures 2 and 3, this catch is substantially U-shaped and is secured within the passage 20 at its upper side by a screw or other suitable fastening device, the spring arms of 80 the catch being adapted to frictionally receive and hold the arm therebetween. For rotating the shaft 21, a key 26 is employed, this key being provided with an elongated 85 shank freely insertable in the boss 23 to engage at its inner end in the socket 22 of said shaft.

As will be readily appreciated in view of the preceding description, by engaging the 100 key 26 in the socket 22, the shaft 21 may be rotated to swing the arm 24 rearwardly to active position, projecting, as particularly shown in Figure 2, toward the valve 15 to engage at its free end with the upper side 105 portion of the valve. Movement of the valve will thus be blocked so that upon removal of the key 26, the valve will be securely locked against operation. Unauthorized use of the vehicle equipped with the device will consequently be effectually obviated. For freeing the valve 15, it is simply necessary to 110

again engage the key in the socket 22 and counter-rotate the shaft 21 until the arm 24 is swung forwardly to horizontal inactive position engaged between the spring arms 5 of the catch 25. The catch will then support the arm and prevent accidental release thereof to possibly interfere with the movement of the throttle valve. It will accordingly be seen that I provide a highly effective construction for the purpose set forth and a device which may be readily applied to substantially any conventional type of motor vehicle engine. However, I do not wish to be limited in this regard since, as will now 10 be appreciated, the device is well adapted for use generally, in connection with internal combustion engines for locking the throttle valves thereof and I, therefore, reserve the right to all such adaptations of the invention as may fall within the spirit of the 15 appended claims.

Having thus described the invention, what is claimed as new is:

1. A throttle valve lock including a body 25 provided with a fuel passage, a shaft journaled in the body, locking means carried by said shaft and movable to active position for blocking movement of a throttle valve, and means carried by the body to coact with the first means for normally holding the first means in inactive position.
2. A throttle valve lock including a body provided with a fuel passage, a shaft journaled upon the body, a locking arm carried 35 by said shaft and movable to active position

for blocking movement of a throttle valve, and a spring catch carried by the body to coact with said arm for normally holding the arm in inactive position.

3. A valve locking unit for interposition 40 between a carbureter and manifold including a body block having a fuel passage therethrough, and a shaft journaled upon the block to intersect said passage and provided with means movable within the passage to project beyond one side face of the block 45 into the path of the throttle valve of the carbureter for engagement by said valve whereby to block the rotative movement of the valve.

4. The combination with a carbureter having a rotatable throttle valve, and a manifold, of a block interposed between the carbureter and manifold and having a fuel passage therethrough, and a shaft journaled 50 upon the block to intersect said passage and provided with an arm movable within said passage to a position projecting beyond one side face of the block in front of the valve for blocking the rotative movement thereof.

5. A throttle valve lock including a body having a fuel passage therethrough, a shaft journaled on the body and provided with an arm movable to active position for blocking movement of a valve, and a substantially U-shaped catch having coacting resilient fingers adapted to grip the arm therebetween 55 for holding the arm in inactive position.

In testimony whereof I affix my signature.
LEROY E. BIGELOW. [L. S.]
